AWNNG CONSTRUCTION

August Bruns, Richmond Hill, N. Y.

Application December 19, 1931, Serial No. 582,018

4 Claims. (Cl. 156—15)

My invention relates to a new and improved awning construction.

One of the objects of my invention is to provide an awning construction so that the awning 5 can be controlled in a simple and efficient manner.

Another object of my invention is to provide an awning construction whereby the awning can be readily raised and lowered, and whereby the awning can be held firmly when it is in the operative position so that the awning will not be caused to rattle by a wind.

Another object of my invention is to provide a device of this type which shall require a minimum number of parts.

Another object of my invention is to provide a device of this type in which the awning can be controlled from the interior of the building.

Another object of my invention is to provide a device of this type which can be simply and efficiently combined with a screen so that the awning can be manipulated from the inside of the room.

Other objects of my invention will be set forth in the following description and drawings which illustrate a preferred embodiment thereof, it being understood that the above general statement of the objects of my invention is intended merely to generally explain the same and not to limit it in any manner.

Fig. 1 is a general perspective view.

Fig. 2 is a sectional view on the line 2—2 of Fig. 1.

Fig. 3 is a sectional view on the line 3—3 of Fig. 1.

Fig. 4 is an enlarged front detail view.

Fig. 5 is a sectional view on the line 5—5 of Fig. 4.

Fig. 6 is a sectional view on the line 6—6 of Fig. 5.

Fig. 7 is an enlarged detail side elevation partly in section.

Fig. 8 is a detail view showing how the screen is perforated.

I have shown my invention as embodied in combination with a screen which is suitably mounted in a window frame, although my invention is not limited to this particular combination.

The screen S has a frame 1, which is suitably mounted in a window frame W.

As shown in Fig. 8, the screen S is provided with an opening 2 through which a part of the operating device can project. The screen S may also be provided with a separate hole 3 through which one of the operating cords may project. The hole

3 may be protected by an eyelet 4. If desired, the hole 2 may be made large enough so as to permit both cords of the operating device to extend through the same.

As shown in Figs. 5 and 6, the operating device 60 includes a housing 5 which can be stamped from metal or made in any other suitable manner and from any suitable material. The housing 5 is provided with parallel and longitudinal vertical walls which are shown in Fig. 7, and these parallel 65 vertical walls are provided with horizontal flanges 5a, which are connected to the frame 1 by means of screws 6 or other suitable fastening devices. The parallel vertical walls of the housing 5 are connected by a front wall or web 5b so that the 70 horizontal cross section of the housing is U-shaped. This front transverse vertical web 5b is provided with an opening through which the pulley P projects. The outer end of the pulley P projects beyond the screen S, as clearly shown 75 in Fig. 5, and the web or wall 5b abuts the inner surface of the screen S. The bottom portion of the web 5b may be provided with an opening through which one of the operating cords 8 may pass. The pulley P is turnably mounted upon a 80 pin 9 which passes through the parallel and longitudinal vertical walls of the housing 5. These parallel and longitudinal vertical walls have notches 18 into which the operating cords may be forced in order to hold said cords firmly 85 against movement.

As shown in Fig. 1, the awning A may be made of any suitable fabric and in any suitable manner. As conventionally shown in the drawings, the top of the awning A is engaged by means of 90 hooks or eyes 10 and said hooks or eyes 10 are also connected to the top of the window frame. The bottom of the awning fabric passes around the lateral branch of a U-shaped bar 11. The inner ends of said U-shaped bar 11 are pivotally 95 connected by means of pins 12 to slides 14, which slide vertically upon bars 15 which are suitably connected to the window frame or to the building. The operating cord 8a passes around the pulley P and then upwardly and around a pulley 16. The 100 operating cord 8a then passes through eyes which are suitably connected to the inner side of the awning A and the outer end of the cord 8a is connected to the lateral branch of the bar 11 in the well known manner. Hence, if the cord 8a 105 is downwardly pulled, the bar 11 is turned upwardly and the slides 14 are then moved upwardly, thus collapsing the awning to the dotted line position illustrated in Fig. 3.

While I have referred to separate cords 8 and 110

8a, I prefer to have these cords integral with each other, so that said cords form a loop which is located within the building.

When the awning is in the operative position shown in full lines in Fig. 3, the cord 8 which is connected to bar 11 and which passes through opening 3, can be pulled tight and said cord 8 can then be caused to engage the notches 18 so that the awning is firmly held in the open or operative position. This is illustrated in Fig. 3, and in Fig. 5.

Likewise, and as shown in Fig. 7, the cord 8a can be caused to engage the notches 18 so that the awning is firmly held in the closed or in-operative position. Likewise, both cords 8 and 8a can be caused to engage the notches 18.

As shown in Fig. 6, the parallel and longitudinal vertical walls of the housing may be provided with outwardly bent and lateral lips 17 and 17a which project through the screen S. The gap between said lips and the screen is filled by means of a U-shaped member 19 which can be forced into the position shown in Figs. 4 and 6. The walls of the member 19 may have a slight transverse taper so that the yoke is firmly wedged into position. The yoke is preferably driven into position after the screws 6 have been forced into the frame 1. In order to install the device, the housing is approximately located in correct position by means of the screws 6 and the member 19 is forced into position. The material of the screen S is bent inwardly around the edge of the opening 2, so that the opening between the housing and the screen is tightly filled by means of the yoke 19. Likewise, the cord 8 can fit tightly in the opening 3, in order to prevent insects from entering the room. It is not necessary to use the lips 17 and 17a and the member 19, because said lips can be eliminated in which case the projecting portions of the parallel and longitudinal vertical walls of the housing would pass through a suitable opening in the screen, and said opening would be substantially filled by the pulley and by the cord 8a. The cord 8a substantially fills the space between the bottom of the pulley and the adjacent part of the web or transverse front wall 5b, in order to prevent insects from entering the room.

The central portions of the parallel and longitudinal walls of the housing (adjacent the pulley P), project beyond the top and bottom portions of the front wall 5b.

The entire operating device can therefore be made in the form of a single unit and a single loop of cord, so that the device can be easily and cheaply installed, as it is only necessary to provide the screen with the openings 2 and 3.

I have shown a preferred embodiment of my invention, but it is clear that numerous changes and omissions can be made provided they come within the spirit and scope of the appended claims.

I claim:

1. In combination with a screen having an opening, a housing held at the inner side of said screen and projecting through said opening, a pulley mounted in said housing, and supplemental means adapted to fill the gap between said housing and the outer surface of the screen.

2. In combination with a screen having an opening, a housing held at the inner side of said screen and projecting through said opening, a pulley mounted in said housing, and supplemental means adapted to fill the gap between said housing and the outer surface of the screen, said housing having laterally extending lips exterior to the screen, and said supplemental means comprising a U-shaped member having legs which are located between said lips and the outer surface of said screen.

3. A device for operating an awning which is associated with a window aperture in a wall comprising a single housing, a pulley mounted in said housing, a first cord adapted to be led underneath said pulley and to raise said awning, a second cord passing through an opening in the same housing and adapted to tightly hold the awning in its open position, retaining means associated with said housing and adapted to hold said cords, said housing being located inwardly of the outer surface of said wall.

4. A device for operating an awning which is associated with a window aperture in a wall comprising a single housing, a pulley mounted in said housing, a first cord adapted to be led underneath said pulley and to raise said awning, a second cord passing through an opening in the same housing and adapted to tightly hold the awning in its open position, retaining means associated with said housing and adapted to hold said cords, said housing being located inwardly of the outer surface of said wall, said retaining means comprising a recessed wall of said housing.
